UNITED STATES PATENT OFFICE

FREDERICK GEORGE HEHR, OF HEMPSTEAD, NEW YORK, ASSIGNOR TO AEROL ENGINE CORPORATION, OF NEW YORK, N. Y., A CORPORATION OF NEW YORK

HYDRAULIC PUMP

Application filed February 27, 1930. Serial No. 431,687.

This invention relates to improvements in internal combustion engines.

It is a primary object of the invention to provide a fuel pump to supply fuel under pressure to the combustion chamber of an engine and to lubricate the fuel pump through devices operated in conjunction with the engine and which will maintain sealed the entire fuel feeding devices.

10 It is a more specific object to provide devices of this character which will prevent the formation of air bubbles in the fuel line.

These and other objects will appear more 15 fully from the following description when considered in connection with the drawings in which:

Fig. 1 is a vertical sectional view of one form which my invention may assume.

20 Fig. 2 is an enlarged detail view of a portion of the apparatus shown in Fig. 1.

In engines of the character disclosed in the drawings, which operate on the solid injection principle, fuel is injected into the 25 engine at the point of highest engine compression and is self-ignited on its introduction into the combustion chamber. The fuel line must be maintained filled with liquid and without any air pockets therein or else 30 the fuel pump cannot uniformly introduce the desired quantity of fuel into the engine. It is to this type of mechanism that the present invention is directed.

Referring to the drawings, I have shown 35 a two-cycle internal combustion engine formed with a cylinder 4, water-jacketed as at 5, and provided with intake and exhaust passages 6 which are exposed only when the piston 7 reaches its inner or lower position 40 where the engine is arranged with vertical piston and cylinder. The piston 7 is connected by a pitman 8 to the crank shaft 9 whereby reciprocation of the piston produces rotation of the crank shaft. The above 45 devices may be of any usual or preferred construction and specifically form no part of my present invention.

At the end of the compression stroke of 50 the piston, fuel is injected into the combustion chamber through the opening 10 and

pipe line 12. The latter may include one-way valves 14 and 15 placed in suitable chambers in the pipe line, the latter being connected to the conduit 16 leading to the bottom of a suitable fuel reservoir 18 which 55 may be the usual float chamber or any other reservoir for fuel.

Fuel is advanced through the pipe line 12 and past the valves 14 and 15 by means of the fuel pump indicated generally at 20. 60 This pump includes a reciprocating piston rod or plunger 22 mounted in a gland 30 supported by the housing 21 and projecting as at 23 into the fuel chamber 24 whereby reciprocation of the plunger produces alternate suction and compression in the chamber 24 for advancing fuel to the engine.

65 The plunger 22 is normally maintained in contact with the surface of a cam 26 by means of a relatively strong spring 27. Cam 26 is rotated in coordination with the rotation of the crank shaft 9 by means of the chain 28 engaged with suitable chain gears on the crank shaft and cam shaft as shown.

70 It will be seen that as the crank shaft approaches the end of the compression stroke for the piston the projecting portion of the cam 26 engages the head of the plunger 22 and moves the advance end 23 of the same upwardly into the chamber 24 thus forcing a predetermined quantity of fuel into the combustion chamber for the power stroke. During further rotation of the crank shaft and cam shaft plunger 22 is 75 retracted thus drawing in fuel in preparation for subsequent operations of the pump.

80 As the fuel is injected into the motor at the time of highest compression an extreme pressure condition exists in the chamber 24 and along the plunger 22 during fuel injection. Fuel is thus forced along the plunger 22 even though the same be snugly fitted within the machined gland 30 forming part of the fuel pump housing 21. Likewise on the suction stroke of the pump air tends to work up between the plunger 22 and the gland 30 and to pass upwardly into the fuel passage. The present invention serves 85 to remove these accumulations of finely 90 95 100

divided air and fuel by means of the following described devices.

The housing 21 is provided with a lubricating duct 32 connected by a suitable pipe 6 to a lubricating pump 34 communicating with a reservoir 36 for lubricating material. The pump 34 (see Fig. 2) may be operated by any suitable devices. As shown these devices include a plunger 37 connected by 10 means of a pitman 38 to a lever 40 pivotally supported upon the pump housing 21. The free end of the lever 40 rests upon the head 22a of the piston rod 22 and is either provided with a spring or mechanical connection 15 as indicated at 42 to maintain the free end of the lever 40 in engagement with the head 22a. The plunger 37 operates in a passage or cylinder 44 and moves upwardly and downwardly under the influence of the 20 piston rod 22. The lubricating pump will operate satisfactorily without valves provided the plunger 37, when in its downward position, uncovers the opening 45 leading from the oil fuel reservoir. On its upward 25 movement the plunger 37 moves up beyond and closes the opening 45 thus forcing a certain quantity of lubricating material 30 through the passage 32. On the retraction of the plunger 37 a reverse flow of a portion of the lubricant is effected but a condition of partial vacuum is established in the passage 32 so that when the plunger uncovers the opening 45 a limited quantity of 35 lubricating oil is drawn into the passage 32, the oil being subsequently advanced through this passage by the lubricating pump. It will be observed that on each operation of the lubricant plunger 37 the oil is advanced through the passage 50 and then retracted 40 to a lesser extent, the forward and reverse flow of oil serving effectively to entrain and remove all particles of fuel and air which reach the recess 50.

The passage 32 leads by way of passage 46 to an opening 48 in the gland 30. The opening 48 extends downwardly from the edge of the gland 30 to the bore of the same constituting the fuel pump cylinder and communicates with a circular recess 50 formed 50 in the interior surface of the gland 30. At the opposite side of the gland a similar upwardly inclined passage 51 leads to a discharge duct 52 which communicates with the fuel reservoir 18. In order to avoid the necessity of an accurate fitting of the gland 30 into the housing 21 either the gland or the housing may be formed with a circular opening 54 so that the passages 46, 48, 51, 52, etc. will be in communication even though the 55 gland is not accurately fitted with these ducts in exact alignment. The opening 54 may be closed for a portion of its length so that the lubricating material cannot bypass around the passages 48, it being sufficient if 60 a reasonable latitude be permitted in the

angular adjustment of the gland 30 in the housing 21.

The lubricating material which I prefer to use is a relatively heavy castor oil, the heavy specific gravity of which causes the lubricating material to remain in the pocket formed by the passages 48, 50 and 51 until forced out through the introduction of additional lubricating material.

A fuel pump constructed as shown herein 75 will operate uniformly to advance and discharge the required amount of fuel into the combustion chamber of the engine.

The body of lubricating material which constantly surrounds the plunger 22 at a 80 point intermediate its length serves to collect the minute particles of air and fuel which tend to pass along the plunger and to pass these particles of material along with the lubricating oil into the fuel reservoir 85 18 where they are subsequently burned with the fuel.

Furthermore the lubricating material supplied by means of the pump 34 will prevent the fuel from the fuel passage working into 90 the mechanism of the fuel pump and destroying the lubricating qualities of the lubricant used therein, whereas if the gland lubricant works into the mechanism, it will be without harmful consequences and the 95 lubrication of the pump mechanism will not be impaired.

Having now described my invention, I claim:

1. In an internal combustion engine, a 100 housing formed with a bearing portion, a fuel pump comprising a reciprocable plunger supported within the bearing portion of said housing, said housing including a circular recess formed in the bearing portion 105 thereof, and a lubricant pump for supplying lubricating material under pressure to said circular recess said pump operating to advance and retract a limited quantity of oil through said recess on each operation thereof.

2. In an internal combustion engine, a 110 housing formed with a bearing portion, a fuel pump comprising a reciprocable plunger supported within the bearing portion of 115 said housing, said housing including a circular recess formed in the bearing portion thereof, and means for supplying lubricating material under pressure to said circular recess, said means including ducts in said housing leading downwardly to said circular recess, one for the supplying of lubricant 120 and the other for the discharge of the used lubricant.

3. In an internal combustion engine, a 125 housing formed with a bearing portion, a fuel pump comprising a reciprocable plunger supported within the bearing portion of said housing, said housing including a lubricant passage formed with a supply por- 130

tion and a discharge portion and a depressed pocket in said passage formed as a circular recess in the bearing portion of said housing, and means for supplying lubricating material under pressure to said lubricant passage.

4. In an internal combustion engine, a force fuel feeding device comprising a vertically arranged fuel feeding plunger and a housing therefor, said plunger and housing being snugly interfit for a substantial portion of the length of the former and being formed with a recess encircling said plunger and means for producing a flow of lubricating material through said recess, said means including ducts extending upwardly away from said recess to form a depressed pocket of the latter.

5. In an internal combustion engine, a force fuel feeding device comprising a fuel feeding plunger and a housing therefor, said plunger and housing being snugly interfit for a substantial portion of the length of the former and means for producing a flow of lubricating material into contact with and past a portion of said plunger where the same is supported within said housing, said means including a depressed pocket encircling said plunger and a plurality of downwardly inclined ducts communicating with said pocket.

6. In an internal combustion engine, a force fuel feeding device comprising a fuel feeding piston rod and a housing therefor for conveying fuel from a fuel reservoir to said engine, said piston rod and housing being snugly interfit for a substantial portion of the length of the former, means for producing a flow of lubricating material into contact with and past a portion of said piston rod where the same is supported within said housing, said means including a depressed pocket encircling said piston rod and a plurality of downwardly inclined ducts communicating with said pocket, a lubricant pump communicating with one of said ducts and means for conducting the used lubricant from the other duct to said fuel reservoir.

50 7. In an internal combustion engine, a force fuel feeding device comprising a fuel feeding plunger and a housing therefor, said plunger and housing being snugly interfit for a substantial portion of the length of the former and means for producing a flow of lubricating material into contact with and past a portion of said plunger where the same is supported within said housing, said means being operated coincidently with the operation of said plunger.

8. In an internal combustion engine, a fuel feeding pump, means for lubricating said pump and comprising a lubricant pump and a restricted lubricant passage, the latter communicating with a reservoir

for lubricating material and with said pump, said lubricant pump closing said passage during a portion of its operation, said passage being otherwise unobstructed throughout its entire length.

9. In an internal combustion engine, a housing formed with a gland constituting a pump cylinder, a fuel pump plunger snugly fitted within said gland and means for lubricating the coacting surfaces of said plunger and said gland and comprising a depressed pocket in said gland and means for supplying lubricant under pressure thereto.

Signed at New York in the county of New York and State of New York this 26th day of February A. D. 1930.
